UNITED STATES PATENT OFFICE.

DWIGHT S. RICHARDSON, OF NEW YORK, N. Y.

GRATE-BAR.

SPECIFICATION forming part of Letters Patent No. 622,077, dated March 28, 1899.

Application filed November 8, 1898. Serial No. 695,882. (No model.)

To all whom it may concern:

Be it known that I, DWIGHT S. RICHARDSON, a citizen of the United States, residing at New York, in the county of New York and State 5 of New York, have invented certain new and useful Improvements in Grate-Bars; and I do hereby declare the following to be a full, clear, and exact description of the same; reference being had to the accompanying drawings, 10 forming a part of this specification, and to the letters of reference marked thereon.

This invention relates more especially to that class of grate-bars which are adapted to be assembled in a group or series and to be 15 operated by connecting - gearing which imparts to all the members of the series a simultaneous reciprocating or rotary movement, although the specific invention here involved relates to the construction of each of the bars, 20 and the advantages arising from the invention will be incident to the use of one or more bars and whether the same be operated independently or in connection with a series of bars. Grate-bars of this class are made angular in cross-section—that is to say, with a 25 series of fuel-supporting faces and with end journals for supporting the bar arranged to take their bearing in a suitable frame or other supporting devices; and the special object of 30 the present invention is to provide a means for more effectually clearing the grate of clinkers which might become wedged either between adjacent bars or between the side bars and the inclosing frame or fire-pot, and 35 in accomplishing this end, according to the present invention, the action of the edge uniting the fuel-supporting faces upon the clinker is augmented by the addition of clinker-cutting projections located on each of the fuel- 40 supporting faces adjacent to but slightly removed from the edge or angle uniting the faces.

Referring to the accompanying drawings, 45 Figure 1 is a top plan view of a simple form of grate with its inclosing and supporting frame and showing clinker-cutting projections. Fig. 2 is a cross-section through one of the grate-bars in its preferred form. Fig. 3 is a similar view showing a grate-bar with 50 straight fuel-supporting faces and illustrating the application of my present invention thereto. Figs. 4, 5, 6, and 7 are detail views

showing different forms of clinker - cutting projections.

Like letters of reference in the several figures indicate the same parts.

The letter A indicates the frame for inclosing and supporting the grate in an ordinary stove, and B B' the grate-bars journaled therein on end bearings b, these grate-bars being 60 preferably geared together at one end, as shown at C in dotted lines, and one of them at its opposite end is provided with an angular projection c for the application of an operating crank-handle or winch. These grate- 65 bars in cross-section intermediate the journals are preferably made triangular, as illustrated in Figs. 2 and 3, and in the most approved form each of the faces is concave, as illustrated in Fig. 2, although it will be 70 understood that this feature is immaterial so far as the spirit of the present invention is concerned. The angles uniting the fuel-bearing faces ordinarily perform a cutting function in freeing the grate from clinkers 75 and like obstructions when such clinkers and obstructions become lodged either between the grate-bars themselves or between the side grate - bars and the sides of the inclosing frame; but experience has shown that such 80 cutting action is imperfect, and as a result the grates are liable to become clogged with clinkers, and in order to overcome this action and secure a more perfect pulverization of the 85 clinkers I now provide clinker-cutting projections on each of the fuel-bearing faces of the bars, as indicated at D in Fig. 4 of the drawings, such projections being located adjacent to, but slightly removed from, the edges of the fuel-bearing faces, so as to act upon different 90 portions of the clinkers from those being acted upon by the angular edges of the bar proper. These clinker-cutting projections in general arrangement follow closely along the edges of 95 the fuel-supporting faces, and it is obvious that they may take a number of different forms. For instance, they may be simple short projections, as at d, Fig. 6, or angular, as at d', Fig. 5, or curved, as at d'', Fig. 7, or they may follow the contour of the edge of the bar 100 where a solid-edged bar is employed, as at d'', Fig. 1. Should the bar be of the well-known sectional type, then each section should be provided with one of these clinker-cutting

projections, the whole line of projections following the general line of the edge of the bar and in any instance being located, as before stated, a slight distance from the edge of the 5 bar itself.

Where the bars are provided with plain or substantially straight fuel-bearing faces, as in Fig. 3, the projections will stand above such faces, although in the preferred construction 10 the clinker-cutting projections are located within the hollow of the concave faces and project but slightly, if at all, above the concavity; but it will be understood that I do not wish to be limited in this respect, inasmuch 15 as the invention is capable of general application to grate-bars which are angular in cross-section and adapted to be rotated about a central axial line. With this arrangement it is found that the clinkers which work down be- 20 tween the adjacent grate-bars or between the side grate-bars and the inclosing frame are caught by the projections and so broken up, by a very easy movement of the operating handle or winch, as to pass through the grate

with the greatest facility, thereby preventing 25 any clogging up of the grate and insuring a free and unobstructed combustion-surface at the bottom of the fire-pot.

Having thus described my invention, what I claim as new is— 30

1. A grate-bar having three fuel-supporting faces and end journals, each of said fuel-supporting faces having clinker-cutting projections adjacent the edges thereof in position to hold the clinkers so as to be acted on by 35 the edges on the adjacent bar; substantially as described.

2. A grate-bar angular in cross-section and having end journals, with clinker-cutting projections running longitudinally along each 40 face slightly removed from the angles uniting the faces and in position to hold the clinkers so as to be acted on by the edges on the adjacent bar; substantially as described.

DWIGHT S. RICHARDSON.
